UNITED STATES PATENT OFFICE.

HARRY W. SHEPARD, OF NEW YORK, N. Y.

DESIGN FOR A MEDAL OR SIMILAR ARTICLE.

40,969.

Specification for Design.

Patented Nov. 8, 1910.

Application filed March 16, 1910. Serial No. 549,803. Term of patent 7 years.

To all whom it may concern:

Be it known that I, HARRY W. SHEPARD, a citizen of the United States, residing at New York city, borough of Brooklyn, county of Kings, and State of New York, have invented a certain new, original, and ornamental Design for Medals or Similar Articles, of which the following is a specification, reference being had to the accompanying drawing, forming part thereof.

The figure is a face view of a medal or similar article showing my new design.

I claim:

The ornamental design for a medal or similar article, as shown.

HARRY W. SHEPARD.
